UNITED STATES PATENT OFFICE

2,438,067

CIRCUIT BREAKER

Hans P. Luhn, Armonk, N. Y., assignor to International Business Machines Corporation, New York, N. Y., a corporation of New York

Application March 17, 1945, Serial No. 583,253

3 Claims. (CL 200—32)

1

This invention relates to circuit breakers and more particularly to a circuit breaker in which contact is repeatedly made and broken through the action of a rotating element.

The principal object of the invention is to provide a simple dependable rotary circuit breaker which will be simple in construction and reliable in operation.

A more specific object of the invention is to provide a circuit breaker in which a rotating element creates a radial stream of mercury through centrifugal action and in which this mercury stream is utilized to make and break circuit connections as the element rotates.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a sectional elevation of the circuit breaker.

Fig. 2 is a plan view taken on the lines 2—2 of Fig. 1.

In the drawings, 10 represents the main body of glass or other suitable insulating material, preferably of a ceramic nature, molded to form a plurality of cups 11 supported in position by radial webs 12. Inserted through the bottoms of the four cups shown are metallic rods 13 which may be connected to suitable circuits. The body 10 is filled with mercury 14 to the level indicated and floating therein is an element 15 which may be termed a rotor, which has a central vertical duct 16 and two radially inclined ducts 17 with intersecting ducts 18 above the level of cups 11. This rotor 15 is also preferably made of ceramic or other insulating material and inserted in its upper face is a permanent magnet 19. The parts are so proportioned, having regard to the quantity of mercury employed, to bring the poles of magnet 19 into close proximity to the cover plate 20, which is of glass or other suitable material. The cover plate 20 is suitably attached so that the chamber formed in the body 10 is hermetically sealed and the air therein is replaced by a gas, for instance nitrogen. Located directly above cover 20 is a second magnet 21, preferably U-shaped, with its poles close to the cover. This magnet is mounted on a shaft 22 and is suitably rotated by a motor or other source of power in synchronism with the machine which the circuit breaker is to control.

Rotation of magnet 21 will, through its mag-

2

netic effect on magnet 19, cause the rotor 15 to turn in unison therewith. As the rotor turns, centrifugal action will force mercury to rise in ducts 16 and branch through ducts 17 and 18 from where a steady stream will extend into cups 11, so that there is an electrical connection between terminals 13 at diametrically opposite sides of the device extending, for example, in Fig. 1 from the left hand terminal 13 through the mercury in the related cup 11, thence through the mercury stream to the left hand ducts 18 and 17, the right hand ducts 17 and 18, and the stream therefrom to the mercury in the right hand cup 11 and right hand terminal 13.

15 It will be noted that the mercury passing to the cups 11 will spill over the rims thereof and drop back into the main body of the mercury or the reservoir so that the level in both the cups and main body will remain relatively constant.

20 As the streams pass the ends of the cup, the circuit connection will be broken, and for the arrangement shown in Fig. 2 it will be noted that contact is made between the left and right hand terminals 13 during the period determined by 25 the arcuate length of the cups on the left and right hand sides.

When the streams reach the upper and lower cups 11, a new circuit connection is effected between top and bottom terminals 13 to complete 30 a circuit therebetween for the period measured by the arcuate length of the top and bottom cups 11. It will be appreciated that the cups 11 may be configured as to their arcuate length, so that the circuit connections established between a pair 35 of cups may be for periods of differing extent during a cycle or revolution of the rotor 15. The provision of the radial ribs 12 serves to retard the tendency of the mercury in the main body to rotate with the rotor 15.

40 While there have been shown and described and pointed out the fundamental novel features of the invention as applied to a single modification, it will be understood that various omissions and substitutions and changes in the form and 45 details of the device illustrated and in its operation may be made by those skilled in the art without departing from the spirit of the invention. It is the intention therefore to be limited only as indicated by the scope of the following 50 claims.

What is claimed is:

1. A circuit breaker comprising a receptacle containing electrically conductive liquid, a rotor supported by the surface of said liquid and rotatable therein, rotating means for the rotor, said

rotor having a radial duct communicating with the supporting liquid whereby upon rotation, liquid will flow through the duct and emit a stream of liquid, a contact element located in the path of said stream whereby as the rotor turns, an electrical connection is completed between the liquid in the receptacle and said contact element.

2. The invention set forth in claim 1 in which the rotor has a permanent magnet integral therewith in its upper surface, and the rotating means comprises a second permanent magnet and means for rotating the same in a plane parallel to the plane of the first magnet, magnetic attraction causing the first magnet to turn with the second.

3. A circuit breaker comprising an enclosed chamber, a quantity of mercury therein extending to a predetermined level, a circular cup within the chamber with the rim thereof above the said level, a rotor supported by said mercury within

said ring, means for rotating the rotor, a radial duct connecting the base of the rotor with a point on its outer surface above the level of the rim of said cup, rotation of the rotor causing mercury to flow by centrifugal action, through said duct into said cup, said cup being filled with mercury whereby the amount received from the duct will pour over the rim back into the base of the receptacle.
